UNITED STATES PATENT OFFICE.

HARRY A. ORME, OF WESLEY HEIGHTS, DISTRICT OF COLUMBIA.

RUDDER FOR AEROPLANES.

1,074,063.

Specification of Letters Patent. Patented Sept. 23, 1913.

Application filed December 31, 1910. Serial No. 600,253.

To all whom it may concern:

Be it known that I, HARRY A. ORME, a citizen of the United States, residing at Beechwood, Wesley Heights, in the District of Columbia, have invented a new and useful Improvement in Rudders for Aeroplanes, of which the following is a specification.

This invention relates generally to aeroplanes and more particularly to a novel construction of rudder and also to the manner of connecting the rudder to the aeroplane and also to the manner of operating the said rudder.

15 The object of my invention is to provide a simple and efficient construction of compound rudder capable of steering or directing the aeroplane and also capable of assisting in elevating or depressing the machine as 20 a whole and also assisting in maintaining the stability or equilibrium of the machine.

Another object of my invention is to provide a compound steering and elevating rudder in which the steering rod and elevating 25 mechanisms are compactly and conveniently arranged within easy reach of the operator.

A still further object is to provide a novel construction of rudder frame connected to the aeroplane proper in such a manner that 30 if the end of the rudder frame should accidentally strike the ground all damage to the aeroplane proper will be averted.

With these objects in view and also with certain other objects which will appear hereinafter, my invention consists in providing 35 a compound steering and elevating rudder; and my invention also consists in providing foot operated means for controlling the steering rudder and hand operated means 40 for controlling the elevating plane of said rudder, said hand and foot controls being within easy and convenient reach of the operator.

The invention consists also in the various 45 details of construction and the novel features of combination or arrangement all of which will be fully described hereinafter and pointed out in the claims.

In the drawings forming a part of this 50 specification: Figure 1 is a perspective view showing a portion of two planes of an aeroplane, the rudder frame connected to said planes and my improved construction of rudder arranged at the rear end of said frame 55 and this view also illustrates the hand and foot operated means for operating the rudder.

der and this view also illustrates the novel manner of bracing or staying the rudder frame and also the novel manner of connecting the rudder frame with the planes of the aeroplane. Fig. 2 is a sectional plan view of the rudder. Fig. 3 is a sectional elevation on the line 3—3 of Fig. 2. Fig. 4 is a detail sectional view on the line 4—4 of Fig. 1. Fig. 5 is a detail sectional view on the line 5—5 of Fig. 3. Fig. 6 is a detail sectional view on the line 6—6 of Fig. 3. Fig. 7 is a detail view showing the manner of connecting the truss rods and converging bars of the rudder frame, and, Fig. 8 is a detail view showing the manner of connecting the upper converging bar to the upper plane of the aeroplane.

This novel construction of rudder is intended or designed to be in connection with the aeroplane patented to me, June 29, 1909, Number 926,593 but it will also be understood that the said rudder and parts connected therewith can also be used in connection with other constructions of aeroplanes

and referring now to the drawings, A, A indicate the planes proper of the aeroplane and B, B the supporting rods connected thereto and connecting the said planes with the skids and other portions of the aeroplane.

C indicates the seat for the operator and D a hand wheel arranged upon the end of a shaft D' which is employed for the purpose of operating the forward planes, (not shown).

E indicates a foot lever pivotally mounted within a frame which projects forwardly from the lower plane and to this foot lever E are connected the steering cords hereinafter referred to.

F are the upper and lower rearwardly converging bars preferably made of wood and each bar may be of a single piece of wood or laminated as preferred. The forward ends of these bars are pivotally connected to the upper surfaces of the upper and lower planes by means of clips F² and it will be noted that by reference to Fig. 8 that said clip F² is arranged directly above the clip B² which connects the supporting rod B and upper plane A, a single bolt A' serving to unite all of the said parts as most clearly shown. As previously described, these bars F converge rearwardly and meet at their rear ends, said meeting ends being securely fastened together and about midway the length of said rods I employ truss

rods F' which are connected to the bars F by means of clips F³ as shown most clearly in Figs. 1, 4, and 7 and the rudder frame is further braced and stayed by means of the upper and lower cross pieces F⁴ and the wires F⁵, said wires extending diagonally from the upper to the lower bars and also from one truss rod to another, but it will be noted that at the rear end of the rudder frame ample space is provided for the movement of the compound rudder.

In constructing this rudder, I employ a vertical steering plane G and a horizontal elevating plane H, said compound rudder being pivotally mounted at the extreme rear end of the rudder frame, and steering cords I, are attached to the horizontal member of the rudder upon opposite sides of the center for the purpose of moving the rudder as a whole from side to side, said steering cords I, passing forwardly over the pulleys I', carried by the truss rods F', and these cords are then connected to the forward lever E, and fastened to a centrally arranged brace or support i², mounted preferably beneath the seat as shown; so that when one end of the foot lever is pushed forward, to push the rudder around, the operating cord will have a compensating movement to permit the rudder to turn and maintain the cord in a fairly taut condition so that the return movement can be easily accomplished when desired. Elevating cords K, are also attached to the horizontal elevating plane preferably at the center thereof, said elevating cords passing over the pulleys K', carried by the rudder frame and at their forward ends are connected to the opposite ends of a hand lever K², pivotally mounted at K³, upon one side of the hand wheel D, so that by means of one hand upon said wheel the operator can shift the hand lever K², as desired in order to raise or lower the horizontal plane of the rudder.

Although I describe the elevating plane H as horizontal, I preferably construct the same upon a slight curve which bears a definite relation to the curves of the planes A and B, but nevertheless I shall refer to this plane H as a horizontal plane inasmuch as it intersects the vertical plane G at substantially a right-angle. The vertical plane G consists of a rudder post G', frame work G², and fabric covering G³, both sides of the frame work being covered and this frame work is braced in any suitable manner to withstand the strain which may be placed thereon. The shape of the vertical plane as a whole is semi-circular as shown. The upper and lower ends of the rudder post are pivotally connected to the rudder frame by means of clips and pivot bolts L, and about midway the height of the rudder post upon the forward side thereof is a clip H', which serves to pivotally connect the front rod H²,

of the horizontal plane to the rudder post, this pivotal connection serving to unite the vertical and horizontal planes and at the same time permit a movement of the horizontal plane independent of the vertical plane, but it will of course be understood that whenever the vertical plane is moved from side to side, it carries with it the horizontal plane also. The horizontal plane is slotted or divided as shown at H³, in order to receive the vertical plane therein and it will be noted that the fabric covering of the vertical plane is slotted as shown at G⁴, in order to permit the up and down movement of the horizontal plane, the extreme rear portion of said horizontal plane working in said slot, which is struck upon an arc, the center of which is the pivotal connection between the vertical and horizontal planes; and the elevating cords K, are connected to the horizontal plane within the vertical plane as most clearly shown in Figs. 2 and 3, said cords passing through the framework of the vertical plane through the rudder post before passing through the guide pulleys K'; such construction being most clearly shown in Figs. 2 and 3.

The forward edges of the horizontal plane are braced by means of suitable wires H⁴ which serve to hold the front portion of the horizontal plane in proper position, the rear portions being free, to a certain extent, depending upon atmospheric pressure to maintain them in their proper positions, and by this it is meant that if the outer rear edges of the horizontal plane should be unduly raised or lowered, atmospheric pressure will very soon return said edges to their normal positions. The horizontal plane H comprises the front rod H², and a series of ribs H⁵, and a fabric covering H⁶, both the upper and lower surfaces being covered.

The rudder frame is connected to the planes of the aeroplane in such a manner that if the lower end of said frame should contact with the ground either in starting or in landing, the rudder frame can have a limited upward movement without transmitting any strain or pressure or twist to the planes of the machine thereby avoiding damage which might occur if the bars of the rudder frame were rigidly attached to the planes of the machine.

From the foregoing description, taken in connection with the accompanying drawings, it will be seen that I provide a novel form of rudder, simple, and durable in construction and highly efficient in operation, as it is only necessary to operate the foot lever E, to steer the machine by moving the rudder as a whole from side to side, and owing to the convenient location of the hand lever K², the horizontal or elevating plane of the rudder can be quickly and easily moved up or down as the occasion may re-

quire, and by having this horizontal rudder plane constructed, arranged and operated as herein shown and described, I not only provide additional stability during the steady 5 forward movement of the machine, but I am also able to maintain or quickly regain stability during any turn or sudden or unusual movement of the machine, as by means of said horizontal plane, the proper impulse up 10 or down can be given to the rudder at the same time that it receives its impulse from one side or the other.

It will thus be seen that I provide a simple, durable and efficient apparatus capable 15 of carrying out of the objects hereinbefore referred to.

What I claim is:

1. The combination with a vertical steering plane having a curved slot, of a horizontal elevating plane, slotted centrally to receive the vertical plane, means for moving the vertical plane from side to side and means for moving the horizontal plane up 20

or down, a rib of the horizontal plane working in the curved slot of the steering plane. 25

2. A rudder for aeroplanes comprising a vertical steering plane, consisting of a rudder post, frame and fabric covering, and a horizontal elevating plane, consisting of a front rod, ribs and fabric covering, said 30 front rod being pivotally connected to the rudder post of the vertical plane, said horizontal plane being centrally slotted or divided to receive the vertical plane therebetween, elevating cords connected centrally 35 to the horizontal plane, said cords being arranged within the vertical plane, and passing through the rudder post, and cords connected to the front rod of horizontal plane, upon opposite sides of the said post, for the 40 purpose specified.

HARRY A. ORME.
